UNITED STATES PATENT OFFICE.

CLARENCE E. BROWN, OF CLARKSBURG, WEST VIRGINIA.

AUTOMATIC SAFETY GATE FOR RAILWAY CROSSINGS.

Application filed March 14, 1921. Serial No. 452,007.

The object of my present invention is the provision of an automatic crossing gate controlled by a train and a vehicle in such manner that the close proximity of both train and vehicle to the crossing are necessary to put the gate into operation i. e., lower the gate which is in normally raised position.

To the attainment of the foregoing, the invention consists in the improvement as hereininafter described and definitely claimed.

In the accompanying drawings, forming part hereof:—

Figure 1 is a general plan view illustrative of the arrangement of my improvement relatively to a railway and a road that intersects the same.

Figures 2 and 3 are elevations taken at right angles to each other and showing the gate arrangement.

Figures 4 and 5 are sections showing one platform and its appurtenances.

Figure 6 is a diagrammatic view illustrative of the electrical arrangement and the electro-mechanical devices employed.

Similar numerals designate corresponding parts in all of the views of the drawings.

Among other elements my improvement comprises a circuit controlling device 1. This device 1 is generally similar to the controlling device disclosed in my Patent Number 1,331,316 of February 17, 1920, and need not therefore be described in detail except to say that it includes a switch 3 and solenoids 1^a and 2, said solenoids being designed to move the switch 3 toward the right and the left so as to cause the switch 3 to contact with the terminals 5 and 4, respectively.

The apparatus also comprises solenoids 6, one of which is shown in Figure 6 in series with the rails 6^x of the railway and an axle 59 of a train when a train moves into the danger or operating zone. Levers 7 are employed in conjunction with the solenoids 6, and the energization of each solenoid 6 serves to bring about rocking of its lever 7 whereby the inner arm of the lever which is weighted as indicated by 7^a will be raised against a stop 7^b. Each lever 7 is arranged substantially as illustrated relatively to a platform 8, the two platforms 8 being located in the operating or danger zone and each adapted to be depressed by the weight of a vehicle when the vehicle is positioned thereon. The apparatus further includes gate units 30, and in combination with each gate unit 30 the apparatus com-

prises a cable drum 31, electric motor 32, a cable 33, a push rod 11, a source of electric energy 34, terminals 9 and 19, Figures 4 and 6, a lever 18, connected at 18^a with a lever 10 and also with the lever 7, terminals 15, 16 and 17 and terminals 12, 13 and 14 Figure 6. At 40 are the bearings of the pivoted, vertically-swingable platforms 8, and at 41 are the weights, with which the platforms are equipped, one weight to each platform, the weights 41 serving to yieldingly maintain the platforms 8 in horizontal position and to return the platform to said position.

As illustrated each gate 30 is preferably in the form of a skeleton steel structure, and I prefer to equip each gate frame designated by 30^x with a red incandescent lamp 42 as illustrated. I would also have it here understood that I prefer to employ a hand switch 43, Figure 6, so that the gate operating means may be put out of commission when desired. The said switch 43 is shown by full lines in Figure 6 in position to render the gate operating means inoperative, and in this connection it will be understood that when the gate operating mechanism is to be operated the switch 43 will be arranged in contact with the terminal 43^a, as indicated by dotted lines in Figure 6. When deemed expedient an audible signal such as an electric bell 44 may be arranged to be put in operation on the closing of the gate shown in Figure 6.

Also when deemed expedient by-passes or roads indicated by 50 in Figure 1 may be provided at the sides of the main road 49 and around the gate units 30, preferably at the right hand sides of the two approaches to the crossing. The said by-passes or roads 50 are adapted to be used with caution by the party in charge of a vehicle at times when the gate units are out of order and are in closed position notwithstanding the absence of an approaching train.

It will be readily understood that when a vehicle moving in either direction depresses one platform 8, a contact will be made between one terminal 9 and the adjacent lever 10, provided said lever 10 has been raised by the energization of the adjacent solenoid 6, and the motor circuit will be completed by the solenoid 1^a moving the switch 3 into contact with the terminal 4 of the controlling device 1. At this time the motor 32 will be operated and the gate unit 30 adjacent to

said platform 8 will be lowered until the gate engages the lower arm 11^x on the push rod 11 and through the medium of a vertically-movable switch member 11^y, Figure 6, including arms 51, 52, 53 and 54 opens the motor circuit at terminals 12, 13 and 14 and closes the switches 15, 16 and 17 to stop the motor 32 and afford the reverse connections to the motor 32 for the subsequent raising 10 of the gate. It follows from this that when a train passes from the operating or danger zone and thereby deenergizes the solenoid 6, the weight 7^a will move the inner arm of the lever 7 downwardly and make a contact between the elements 18 and 19 with the result that the circuit including the solenoid 2 will be completed, and the said solenoid 2 will move the switch 3 toward the right and thereby again complete the motor circuit 20 and raise the gate 30 to its uppermost position. When the gate strikes the upper arm 11^x of the push rod 11 incident to the upward movement of the gate, the circuit will be opened at the points 15, 16 and 17, the 25 motor will be stopped, and the gate will be suspended and held in raised position in readiness for operation when the next train and vehicle concurrently enter the operating or danger zone.

Manifestly the source of energy 34 may when expedient be a storage battery or a wet cell battery and the motors 32 may each be of a capacity of from 6 to 12 volts so as to be properly operable by the said battery.

By reference to Figure 6 it will be understood that the dotted line representation designated by 59 is a train on the railway track 6^x and is disposed in close proximity to the intersecting roadway 49, and it will 40 also be understood that the main return wire of the electric system, i. e., the wire that leads to the negative pole of the source of electric energy 34 is designated by the numeral 66, while one of the wires in connection with 45 the positive pole of the source of energy 34 is designated by 60 and the other wire by 60^x which is interposed between the solenoid 6 and the source of energy 34.

When the switch 43 is in the dotted line 50 position as shown in Figure 6, the mechanism is in readiness for operation. Therefore, when a train as disclosed at 59 reaches a predetermined point spaced from the roadway 49, the apparatus or mechanism for 55 operating the gate 30 will be put in readiness for the lowering of the gate which will be lowered provided a vehicle passes over and depresses either of the platforms 8, but in the event that a vehicle does not depress 60 either of the platforms and the train 59 is disposed as shown, current passes from the source of energy 34, through the wire 60^x to the solenoid 6, and from the solenoid 6 to the switch 43 through the wire 65, thence to 65 one track 6^x through the wire 67, through

the car wheels of the train 59 and the other track 6^x, through the wire 68, wire 69, wire 66 and to the negative side of the source of energy 34, thereby it will be apparent that the solenoid 6 has been energized to raise 70 the weight 7^a and the lever 7 against the stop 7^b, and also pulls the lever 18 out of contact with its terminal 19, and lifts the lever 10 nearer to the terminal or contact 9, but not in contact therewith, this action is 75 all that takes place while the train is in position as indicated, the train operating to hold the mechanism in this position until the same has passed beyond the predetermined zone adjacent the roadway 49, then 80 the solenoid 6 is deenergized and allows the weight 7^a to return to the respective levers to their normal position as shown in Figure 6.

It will be noted that the six wire connections, namely; the solenoid 6, terminal 9, 85 lever 10, lever 18, and terminal 19 are each provided with a branch wire which extends to the similar elements of the platform which is arranged opposite the platform 8 illustrated at the bottom of said Figure 6, 90 it being understood that the circuit arrangement is the same for the two sets of platform appurtenances referred to, and if neither of the platforms 8 are depressed the gate will not be lowered notwithstanding 95 the proximity of the train to the crossing or roadway 49.

In the event that a train 59 is near the roadway 49 and either of the platforms 8 are depressed, it will be apparent from the 100 above that the solenoid 6 is energized and the lever 10 is raised so that the weight of a vehicle by depressing the platform will cause a contact to be made between the lever 10 and the contact terminal 9. When this action takes place the current goes from the positive side of the source of energy 34 to the switch blade 3 through the medium of the wire 60 and thence crosses to the terminal 5 to the lever 10 through the medium 105 of the wire 61 and thence to contact 9 through wire 62 to the solenoid 1^a and back to the negative side of the source of energy 34 through wires 63, 64 and 66 so as to energize the solenoid 1^a to pull the switch blade 3 out of contact from terminal 5 with sufficient momentum to arrange the switch blade 3 into contact with the terminal 4 as will be readily apparent. When this last mentioned circuit has been completed, the current goes from the source of energy 34 to the switch blade 3, to contact terminal 4, through wire 80, wire 83 through electric bell 44, through wire 85, to lamp 42, through wire 86, wire 69, and thence through wire 66 110 to the negative side of the source of current. This circuit is adapted to light the lamp 42 and ring the bell 44, as the gate begins to rise. It will also be seen that the current 115 will travel to the lever 18 through the medi- 120

um of the wire 81 as shown and as this lever 18 is out of contact with the member 19, this source of current terminates with the lever 18. The current also goes to the terminal 14, also through the medium of the wire 81 and crosses the terminal 54 to shunt field of motor and thence goes back to the negative side of the source of energy through the medium of the wire 82, and the wire 66. This passage of current will energize the shunt field of the motor and it will also be noted that the current further extends to the terminal 12, crosses the terminal 52 to the armature of motor, back to the terminal 53 and terminals 13 and 17 and thence back to the negative side of the source of energy through the medium of the wire 99, wire 82 and wire 66 thereby running the motor and causing the gate to descend and obstruct the roadway, the gate in descending will strike the arm 11^x with the result the switch 11^w is lowered and opens the motor circuit by causing the terminals 52 and 54 to be arranged out of contact with the terminals 12 and 14 thus stopping the motor with the gate in its downward position with the bell ringing and the lamp burning. The rod 11 is frictionally held in the sleeves 11^a and therefore it will be obvious that the descending of the gate will not be accompanied by the dropping of the rod until the gate engages the arm 11^x. The push rod 11 when in its down position also causes the terminals 51, 52 and 53 to contact terminals 15, 16 and 17 and the gate will remain in its closed position as long as the train holds the solenoid 6 energized, but when the train has passed beyond the zone near the roadway 49, it will be obvious that the solenoid 6 will be deenergized with the result that the weight 7^a pulls the lever 18 back in contact with the terminal 19 or in the position as shown in Figure 6, and then the current will follow from the source of energy 34 to the switch blade 3 through the wire 60 thence to terminal 4 and to the lamps and bell through the wires as above set forth and it should here be noted that the lamp and bell has been ringing the entire time that the train is within the zone about the roadway 49, the current also flows to the terminals 14 and 12 through the respective wires as above set forth, but it will be remembered from above that the motor current is open as the switch 11^w is arranged in its downward position, with the result that the current will go to the lever 18, contact terminal 19, thence to solenoid 2 through the medium of the wire 90 so as to pull the switch blade 3 out of contact with the terminal 4 thereby opening the circuit of the solenoid 2 and with sufficient momentum that the lever 3 contacts with the terminal 5, the current will then go to the lever 10 through the medium of the wire 61 as shown, but since the lever 10 is out of contact from the terminal 9 the current will stop with the lever 10, but the current will also rise to the terminal 51 through the medium of the wire 93 and the terminal 51 has been lowered in that the rod 11 is in its lowermost position, this terminal 51 is in contact with the terminal or contact button 15, from the terminal 15 the current goes to the shunt field of the motor through the medium of the wires 95 and 96 and thence to the negative side of the source of energy in the same manner as above set forth, thereby energizing the shunt field of the motor, the current further goes to the terminal 16 through the medium of the wire 94, but it must be remembered that the rod 11 is in its downward position and not as shown in Figure 6, with the result the current will flow from the terminal 16 through the terminal 53 thence to the armature of the motor in the opposite direction from the direction taken when it runs the gate down, from the armature of the motor the current returns to the terminal 52 through the medium of the wire 98, thence to the terminal 17, terminal 13 and back to the negative side of the source of energy through the medium of the wire 99, wire 92 and wire 66 thereby causing a reverse of the current in the armature for running the gate to its uppermost position. When the gate reaches its uppermost position it will strike the upper arm 11^x and returns the switch 11^w to its normal position as disclosed in Figure 6, thereby opening the shunt field of the motor by leaving the terminal 15 and opening the armature of the motor by leaving the terminals 16 and 17, thereby stopping the motor and leaving the gate in its uppermost position with all of the mechanism ready for the next train and vehicle.

It will be noted that the circuit for the solenoid 6 is shown by full line arrows in Figure 6 while the circuit for the motor, bell, lamp, and the reversing switch which includes the terminals 51, 52, 53, 54 terminals 15, 12, 17, 13, 16 and 14 is shown by arrows in dotted lines so that these respective circuits may be distinguished. When referring to the solenoid 6 with respect to the arrows in full lines it will also be noted that the arrows in full lines take in the circuit for the entire platform appurtenances. The hand switch 43 when thrown to the left in Figure 6 so as to engage the left hand terminal will also close the gate and this switch is primarily designed for the gate keeper so he can actuate said gates without waiting for a passing of a train to ascertain whether or not the gates are in running order.

Having described my invention, what I claim and desire to secure by Letters-Patent, is:—

1. A railway crossing gate, in combina-

tion with electro-mechanical means to put the gate into operation; said means including a device controlled by a train when in an operating or danger zone, and a second device operated by a vehicle when in an operating or danger zone, whereby close proximity of a train and vehicle are necessary for the movement of the gate into working position.

2. A railway crossing gate, in combination with electro-mechanical means to put the gate into operation; said means including a device controlled by a train when in an operating or danger zone, and a second device operated by a vehicle when in an operating or danger zone, whereby close proximity of a train and vehicle are necessary for the movement of the gate into working position, and the train device including a solenoid, and the vehicle device a platform and circuit closing means, and the circuit closing means being associated with the gate.

3. A railway crossing gate, in combination with electro-mechanical means to put the

gate into operation; said means including a device controlled by a train when in an operating or danger zone, and a second device operated by a vehicle when in an operating or danger zone, whereby close proximity of a train and vehicle are necessary for the movement of the gate into working position, and means associated with said gate to raise and lower same.

4. A railway crossing gate, in combination with electro-mechanical means to put the gate into operation; said means including a device controlled by a train when in an operating or danger zone, and a second device controlled by a vehicle when in an operating or danger zone, whereby close proximity of a train and vehicle are necessary for the movement of the gate into working position, the said devices being so constructed and arranged that the gate cannot be returned to idle position until after the train moves out of the danger zone.

In testimony whereof I affix my signature.

CLARENCE E. BROWN.
